UNITED STATES PATENT OFFICE.

FRANK M. ROBINSON, OF ALLENTOWN, PENNSYLVANIA.

PENCIL-SHARPENER.

SPECIFICATION forming part of Letters Patent No. 756,287, dated April 5, 1904.

Application filed December 8, 1903. Serial No. 184,321. (No model.)

To all whom it may concern:

Be it known that I, FRANK M. ROBINSON, a citizen of the United States, residing at Allentown, in the county of Lehigh, State of Pennsylvania, have invented certain new and useful Improvements in Pencil-Sharpener, of which the following is a specification, reference being had therein to the accompanying drawings.

10 This invention relates to a pencil-sharpener, and particularly to a construction for imparting a planetary movement to the sharpening-rolls.

The invention has for an object to provide 15 a construction whereby the sharpening-rolls may be mounted at their opposite ends in rotatable disks, one of which is driven, while each of the rolls is provided with a gear adapted to mesh with a fixed series of gear-teeth 20 whereby the rolls are individually rotated about their axes and also about the axes of the supporting-plates at the opposite ends thereof.

A further object of the invention is to provide 25 an improved construction of the detail features of the sharpener whereby the construction thereof may be simplified and economized, while a most efficient action is secured in the operation thereof.

30 Other and further objects and advantages of the invention will be hereinafter set forth and the novel features thereof defined by the appended claims.

In the drawings, Figure 1 is a perspective. 35 Fig. 2 is a central vertical section. Fig. 3 is a detail perspective of the driving-disk. Fig. 4 is a similar view of the internal gear. Fig. 5 is a perspective of the sharpening-rollers, and Fig. 6 is a similar view of the supporting-disk.

40 Like letters of reference refer to like parts in the several figures of the drawings.

The device may be mounted upon any suitable form of frame and standard, one form of 45 which is herein shown, where the letter A designates a standard having a foot A' at its lower end, adapted to be secured to a fixed support, while at the upper portion thereof a back plate A² is secured. Supported from this 50 back plate is a front plate A³, connected in

any desired manner—for instance, by the side bars A⁴—while the front plate is provided with a tubular pencil-holder A⁵, extended through the plate at its inner face, as shown at A⁶. Supported from the back plate A² is an internal 55 gear-plate B, which may be held in position by means of posts or screws B' and is provided with a centrally-disposed aperture B², having a series of peripheral gear-teeth B³.

The driving-disk C is disposed parallel to 60 the gear-plate B and adjacent to the back plate A² and journaled therein by means of the spindle C', upon the end of which the driving-pinion C² is secured, which pinion is adapted to mesh with the driving-gear C³, pivotally 65 mounted upon the standard at C' and provided with an operating-handle C⁵. This driving-disk is provided with bearing-sockets C⁶ upon its inner face adapted to receive the pintles D' at one end of the grinding-rollers D, which 70 are mounted at an angle to each other, and upon the same end of which the gear D² is also provided and adapted to engage the teeth B³ of the internal gear-plate. These rollers may 75 be of any desired construction—for instance, formed of wood or equivalent material and coated with emery for the purpose of forming an abrading-surface to engage the pencil inserted between the same. The opposite 80 ends of these rollers are provided with pintles D³, adapted to seat in sockets E', formed in the rotatable supporting-disk E, which is provided with a central aperture E², adapted to fit over the extended end A⁶ of the pencil-holder and rotate thereon.

In the operation of the invention it will be seen that power transmitted from the driving-wheel will through the geared connection readily rotate the driving-disk and carry therewith the grinding-rollers and the supporting-disk at the opposite end thereof, rotating the same about the axes of said disks. During this rotative movement the gears upon the ends of the rollers engage the teeth of the internal gear-plate, thus rotating the rollers 95 upon their own axes simultaneously with the first rotation, thereby providing a planetary motion for the cutters, which has been found especially efficient in this art. The construction herein shown has been found to be adapt- 100

ed to grind the wood at the pencil-point without danger to the lead therein, and the construction of the several parts is such that they may be simply and economically formed by 5 machinery and assembled without the use of skilled labor. Furthermore, the construction permits the use of a desirable extended grinding-surface and firmly supports the rollers during the planetary movement thereof.

10 It will be obvious that changes may be made in the details of construction and configuration without departing from the spirit of the invention as defined by the appended claims.

Having described my invention and set forth 15 its merits, what I claim, and desire to secure by Letters Patent, is—

1. In a pencil-sharpener, a frame, a driving-disk mounted therein, rollers pivotally mounted at one end in said disk, a supporting-disk 20 rotatably mounted upon said frame for pivotally mounting the opposite ends of the rollers, and means for rotating said driving-disk.

2. In a pencil-sharpener, a frame, a driving-disk mounted therein, rollers pivotally mounted 25 at one end in said disk, a supporting-disk rotatably mounted upon said frame for pivotally mounting the opposite ends of the rollers, means for rotating said driving-disk, gears upon said rollers, and a fixed internal gear 30 spaced from the frame parallel to the driving-disk for engaging said roller-gears.

3. In a pencil-sharpener, a frame, a driving-disk mounted therein, rollers pivotally mounted at one end in said disk, a rotatable supporting-disk for pivotally mounting the opposite ends of the rollers, means for rotating 35 said driving-disk, gears upon said rollers, an internal gear engaging said roller-gears, and a pencil-holder carried by the frame to provide a bearing for the supporting-disk.

4. In a pencil-sharpener, a standard, a frame comprising front and back plates connected together, a driving-disk pivotally supported in the back plate, a supporting-disk pivotally 45 supported upon the front plate, and rollers having their pintles mounted in said disks and disposed with their operating-faces at an angle to each other.

5. In a pencil-sharpener, a standard, a frame comprising front and back plates connected 50 together, a driving-disk pivotally supported in the back plate, a supporting-disk pivotally supported upon the front plate, rollers having their pintles mounted on said disks and disposed with their operating-faces at an angle 55 to each other, an internal gear-plate rigidly supported from the back plate, and gears carried by each of said rollers to engage the internal gear-plate.

6. In a pencil-sharpener, a standard, a frame 60 comprising front and back plates connected together, a driving-disk pivotally supported in the back plate, a supporting-disk pivotally supported upon the front plate, rollers having their pintles mounted in said disks and disposed with their operating-faces at an angle to each other, an internal gear-plate rigidly supported from the back plate, gears carried by each of said rollers to engage the internal gear-plate, and a pencil-holder projected from 70 the front plate and extended beyond the inner face thereof to form a bearing for the supporting-disk.

7. In a pencil-sharpener, a standard, a frame comprising front and back plates connected 75 together, a driving-disk pivotally supported in the back plate, a supporting-disk pivotally supported upon the frame, rollers having their pintles mounted in said disks and disposed with their operating-faces at an angle to each other, an internal gear-plate rigidly supported from the back plate, gears carried by each of said rollers to engage the internal gear-plate, a pencil-holder projected from the front plate and extended beyond the inner face 85 thereof to form a bearing for the supporting-disk, a pinion upon the shaft of the driving-disk, and a driving-gear pivotally mounted upon an upright to mesh with said pinion.

In testimony whereof I affix my signature in 90 presence of two witnesses.

FRANK M. ROBINSON.
